UNITED STATES PATENT OFFICE

EDWARD J. BRANDT, OF WATERTOWN, WISCONSIN, ASSIGNOR TO BRANDT AUTOMATIC CASHIER CO., OF WATERTOWN, WISCONSIN

ADJUSTABLE SPOUT

Application filed April 9, 1926. Serial No. 100,903.

This invention pertains to improvements in coin delivery spouts for use in connection with change or coin delivery machines of various types, such as paying or change-making machines, wherein it is desired to deliver certain coins direct to a customer without the necessity of handling the same.

In the use of machines of the character described, which are usually portable, the same are placed upon convenient counters, desks, or other suitable articles of support, and heretofore considerable difficulty has been encountered in conveniently placing the machine for the operator and with relation to the various arrangements of fixtures encountered, and at the same time permitting the delivery of coins to a location from which they may be conveniently removed by the customer.

It is therefore the primary object of the present invention to provide a coin delivery spout, for machines of the character described, which may be adjusted with relation to the machine to deliver coins to any desired point within a predetermined area about the machine.

Incidental to the foregoing a further object resides in the provision of a coin delivery spout or trough which is adjustably attached to the exterior of a coin delivery machine, and a coin receiving cup adjustably carried by the free end of the spout.

With the above and other objects in view, which will appear as the description proceeds, the invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings is illustrated one complete example of the physical embodiment of the present invention constructed according to the best mode so far devised for the practical application of the principles thereof.

Figure 1 is a plan view illustrating the in-

vention attached to a conventional type of coin delivery machine.

Figure 2 is a transverse section taken through the machine, as indicated by the line 2—2 of Figure 1.

Figure 3 is a longitudinal section through the coin delivery spout and a portion of the machine to which it is attached.

Figure 4 is a bottom plan view of the spout.

Figure 5 is a detailed section taken on the line 5—5 of Figure 3.

Figure 6 is a detailed section through a portion of the spout taken on the line 6—6 of Figure 3, and

Figure 7 is an elevational view of that portion of the spout comprising the connection between the trough and the coin receiving cup.

Referring now more particularly to the accompanying drawings, the numeral 50 designates a casing of a conventional type of coin delivery machine, the same being shown more or less diagrammatically, inasmuch as its specific structure forms no part of the present invention. Mounted within the casing is an inclined chute 51 having its ends supported by the sides of the casing, and intermediate its ends the chute is secured in any suitable manner to a bracket 52 carried by the casing. The opposite sides of the casing are provided with openings 53, one of which provides for the discharge of coins from the machine. From the method of mounting the chute 51 within the casing, as best shown in Figure 2 of the drawings, it will be seen that the chute may be arranged to discharge to either side of the casing and when the chute has been selectively attached in the desired position, the opening opposite the discharge end of the chute is closed by means of a plate 54 attached in any suitable manner.

Adjacent the opening 53, through which coins from the chute are discharged, a bracket 55 is attached to the exterior of the casing by means of a flange 56 which may be screwed or bolted to the casing. The bracket 55, is constructed in the form of a shell provided with a side opening 54', which is adapted to align with the opening 53 in the casing, and at its bottom the bracket is provided with an annu-

lar opening 56' for the reception of an inclined trough, as will be hereinafter explained.

The inclined trough 57 is provided at its upper end with a vertical elbow 58, which carries an annular band 59 adapted to be received within the bottom opening 56 of the bracket. The bottom of the bracket is split radially at 60 and a screw 61 threaded transversely of 10 the slit 60 serves to contract the opening 56 to engage and lock the annular band 59 in any one of its pivotally adjusted positions.

The lower end of the trough 57 is provided with a vertical wall 62 which serves as an end 15 closure to retard the travel of the coins down the trough and direct them downwardly through an opening 63 provided at the bottom of the trough.

Depending from the trough 57 is a lug 64 20 to which is secured an annular bracket 65 which is provided in its bottom with a circular opening 66 for the reception of a stud 67 carried by the bottom of a coin receiving cup 68.

25 The cup 68 is elongated, as shown in Figures 1 and 3, and has its bottom inclined downwardly toward the outer end. The inner end of the cup, which carries the stud 67, is positioned directly below the opening 63 in 30 the trough 57. Thus, the coins passing down the trough will be discharged through the openings 63 into the cup where they can be removed by the customer. As shown in Figures 3 and 4, the bottom of the bracket 65 is 35 slotted radially and a screw threaded in the bottom transversely of the slit serves to contract the opening 66 to engage and lock the stud 67 in any one of its lateral adjusted positions.

40 From the foregoing description it will be readily seen that by the arrangement of the spout provided the coin receiving cup may be positioned at any point within a predetermined area about the machine, by means of 45 the pivotal adjustment of the trough with relation to the bracket 55, and the pivotal adjustment of the cup 68 with relation to the free end of the trough 57.

In the use of coin delivery machines, the 50 same are often placed on counters provided with wickets or windows W, indicated in dotted lines in Figure 1, and it will be readily appreciated that in order to place the machine in a position for convenient operation, it is essential and important that the delivery spout permit of adjustment in order that 55 the coin receiving cup may be properly positioned with relation to the wicket, or other position within reach of the person removing the coins. This is accomplished in a simple and efficient manner by the foregoing structure which will allow the machine to be placed in any position with relation to the surrounding fixtures, and at the same 60 time will permit the delivery spout to be 65

quickly adjusted to accommodate various arrangements, such as is disclosed by the various dotted positions of the spout in Figure 1.

In the drawings the spout is shown attached to the left side of the machine and adjusted to deliver coins to the rear thereof. In the event it is desired to deliver coins to the opposite sides of the machine, the plate 54 is removed and the bracket 55 is secured 75 in its place, as disclosed in dotted lines in Figure 1, and the plate 54 is then utilized to close the opening on the left side of the machine. To accommodate the foregoing arrangement the chute 57 is removed and 80 mounted in reverse position to discharge coins to the right side of the machine.

As illustrated and described, the trough and receiving cup may then be adjusted to discharge to any position within a limited 85 area about the machine which includes that position shown in dotted lines at the right of the machine in Figure 1.

It will be noted that I do not claim herein 90 my invention comprising the combination involving the use of the spout and connections enabling adjustment of the spout forwardly and backwardly or the various positions around the end of the device, such being the subject matter of my earlier application Serial No. 715,661, filed May 24, 1924, 95 the present application being devoted to my invention involving the use of the two point adjustable relationship of the spout and cup.

I claim:

1. In combination with a coin delivery machine, a coin delivery spout comprising a bracket for attachment to one side of said machine, said bracket having an opening in its side adjacent said machine and openings in its top and bottom, an inclined open trough provided with an opening in its lower end and having its upper end rotatably adjustable within the bottom opening of said bracket, a bracket carried by the lower end of said trough, and a horizontally disposed coin receiving cup adjustably carried by said trough and aligned with the opening in the lower end of said trough, said cup being positioned closely adjacent the table or machine support.

2. A coin delivery spout comprising a bracket for attachment to a coin delivery machine, said bracket having an open top and bottom and an opening in the attaching side 120 through which coins enter, an open inclined trough provided with a vertical end wall at its lower end and an opening in its bottom adjacent said wall, and having its upper end rotatably connected to the bottom of said bracket to receive coins therefrom, a bracket carried by the lower end of said trough, an open coin receiving cup provided with a depending lug at one end thereof and journaled 125 in said trough bracket, said receiving cup 130

having one end communicating with the opening in said trough and its opposite end projecting beyond said opening, whereby coins may be readily removed from the cup,
5 means for locking the cup in adjusted position with relation to the trough, and means for locking the trough in adjusted position.

3. The combination of a coin delivery machine, a coin delivery spout comprising a bracket for attachment to one side of said machine, said bracket having an opening in the side adjacent said machine, and openings in its top and bottom, an inclined open trough provided with an opening in its lower end
10 and having its upper end adjustably connected to said bracket and alined with its bottom opening, and a horizontally disposed receiving cup adjustably carried by the lower end of said trough and alined with the opening therein, said trough being positioned closely adjacent the table or machine support.

4. The combination of a coin delivery machine, a coin delivery spout comprising a bracket for attachment to one side of said machine, said bracket having an opening in its side adjacent said machine, and openings in its top and bottom, an inclined open trough provided with an opening in its lower end and having its upper end adjustably connected to said bracket and alined with the bottom opening therein, a horizontally disposed coin receiving cup alined with the opening in the lower end of said trough, and interengaging means between said cup and
25 trough to permit relative horizontal adjustment of the two, said cup being positioned closely adjacent the table or the machine support.

5. The combination of a coin machine, a coin delivery spout comprising a bracket for attachment to one wall of the machine, said bracket having an opening in communication with the machine, an opening in the bottom of the bracket, a downwardly inclined trough provided with an opening in its lower end and having its upper end adjustably connected to said bracket and alined with its bottom opening, and a receiving cup adjustably carried by the lower end of said trough and
45 alined with the opening therein.

In testimony that I claim the foregoing I have hereunto set my hand at Watertown, in the county of Jefferson and State of Wisconsin.

55 EDWARD J. BRANDT.
